UNITED STATES PATENT OFFICE.

EDWIN FRANCES, OF CALAIS, FRANCE.

DESIGN FOR LACE FABRIC.

SPECIFICATION forming part of Design No. 22,314, dated March 28, 1893.

Application filed February 17, 1893. Serial No. 462,774. Term of patent 3½ years.

To all whom it may concern:

Be it known that I, EDWIN FRANCES, a citizen of France, and a resident of Calais, France, have invented and produced a new and original Design for Lace Fabric, of which the following is a specification, reference being had to the accompanying drawing, showing a part thereof.

The drawing represents a piece of my newly designed lace fabric.

The leading feature of my design consists of an arc-shaped ornament surmounted by a branch and provided at the base with rosettes and leaves.

a, represents an arc-shaped ornament sur- 15 mounted by a plume or branch *b*, carrying ovals *c*. At the lower end of the arc-shaped ornament there are arranged rosettes *d*, and leaves *e*.

What I claim is—

The design for a lace fabric, substantially as shown and described.

Signed at Calais, in the Republic of France, this 3d day of February, A. D. 1893.

EDWIN FRANCES.
